DESIGN FOR A COMBINED SLIDE AND GRIP BUCKLE

Daniel Kasen, Newark, N. J.

Application June 15, 1942, Serial No. 107,206

Term of patent 3½ years

To all whom it may concern:

Be it known that I, Daniel Kasen, a citizen of the United States of America, residing in Newark, county of Essex and State of New Jersey, have invented a new, original, and ornamental Design for a Combined Slide and Grip Buckle, of which the following is a specification, reference being had to the accompanying drawing, forming part thereof, wherein

Figure 1 is a front view of a combined slide and grip buckle showing my new design.

Figure 2 is a rear view thereof, and

Figure 3 is a slide elevational view.

Figure 4 is a front view of the grip member of the combined slide and grip buckle, shown in Figure 1.

Figure 5 is a side elevational view thereof.

Figure 6 is a front view of the slide member of the combined slide and grip buckle, and

Figure 7 is a side elevational view thereof.

I claim:

The ornamental design for a combined slide and grip buckle, substantially as shown.

DANIEL KASEN.
